UNITED STATES PATENT OFFICE.

LOUIS P. HILDEBRAND, OF SAN MARCIAL, NEW MEXICO.

DESIGN FOR A STOVE.

45,529.

Specification for Design.

Patented Mar. 31, 1914.

Application filed January 3, 1914. Serial No. 810,268. Term of patent 14 years.

To all whom it may concern:

Be it known that I, LOUIS P. HILDEBRAND, a citizen of the United States, residing at San Marcial, in the county of Socorro and State of New Mexico, have invented a new, original, and ornamental Design for Stoves, of which the following is a specification, reference being had to the accompanying drawing, forming part thereof.

The figure is a side elevation of my improved stove.

I claim:

The ornamental design for a stove, substantially as shown.

LOUIS P. HILDEBRAND.

Witnesses:

CHARLES GOEBEL,
ERIC JOHNSON.
